CHILD'S SAVINGS BANK

James Donald Johnson, 5015 Bear Ave. NE,
Cannonsburg, Mich.

Filed May 25, 1962, Ser. No. 70,288

Term of patent 14 years

(Cl. D34—11)

The side, bottom, and rear of the article not shown are plain.

I claim:

The ornamental design for a child's savings bank, as shown and described.
